METHOD OF AND APPARATUS FOR REFINING FRUIT SAUCES

William A. Smith, Lyndonville, N. Y.

Application December 27, 1935, Serial No. 56,356

22 Claims. (Cl. 210—1)

The present invention has for its object to provide an improved method and apparatus for refining or clarifying fruit sauces by effectively and economically removing objectionable or 5 foreign particles therefrom.

A further object of the invention is to provide an improved method by which to effect removal of various foreign particles from fruit sauces and other semi-liquid materials, which embodies the 10 spreading or flowing of the materials on a supporting surface and employing suction producing means to pick out or withdraw from the materials the foreign particles contained therein.

A further object of the invention is to provide 15 an improved method embodying the use of suction or vacuum producing means for removing the foreign particles from fruit sauces and other materials and for recovering or collecting such portions of the material as may be contiguous 20 to and withdrawn with said foreign particles.

A further object of the invention is to provide 25 improved apparatus for effectively and economically handling and refining fruit sauces and other materials to be treated, and for carrying 30 out the several steps of the method or methods described herein.

To these and other ends the invention resides 35 in certain improvements and combinations of parts, all as will be hereinafter more fully described, the novel features being pointed out in 40 the claims at the end of the specification.

In the drawings:

Fig. 1 is a side elevation of apparatus constructed in accordance with the invention;

Fig. 2 is an end elevation drawn to an enlarged scale and illustrating the means for supporting the film or layer of material to be refined or clarified;

Fig. 3 is a detailed view drawn to an enlarged scale and illustrating one of the suction nozzles and the hand grip therefor shown in Fig. 1;

Fig. 4 is a fragmentary side elevation of a modified form of the invention;

Fig. 5 is a view drawn to an enlarged scale and partly in section illustrating a modified form of nozzle;

Fig. 6 is a fragmentary part sectional view showing the valve illustrated in Fig. 5 in closed position, and

Fig. 7 is a view illustrating modified means for supporting and advancing a thin layer of the material to be refined or clarified.

The same reference numerals throughout the 55 several views indicate the same parts.

In paring, coring and slicing fruits, such, for example as apples, preparatory to making fruit sauces, it is difficult to eliminate all undesirable or foreign particles from the prepared material, such as the seeds or seed particles, portions of 5 the skin and core, and discolored or defective portions of the apples. The presence of such particles or portions within the sauce is detrimental for various reasons, not only because they detract from its appearance and adversely 10 affect the sale of the product, but render it objectionable from the consumers' standpoint as well.

The invention has for its object to provide a new and efficient method for effecting removal 15 of such particles from the sauce, before delivering it to the cans or containers in which it is to be sold or placed on the market, the removal of such particles being preferably effected upon discharging the sauce from the apparatus em- 20 ployed to effect cooling of the same. Improved apparatus for carrying out the method is also provided as described hereinafter.

Generally speaking the method includes 25 spreading or flowing the sauce on a belt or table in a relatively thin film or layer and employing suitable suction means to remove the foreign particles from the sauce, either while flowing it or while it is in a stationary condition, the particles being made readily visible by reason of the 30 thinness of the layer. It is preferred to flow the sauce on the table by gravity, which simplifies the method and shortens the time of operation, as distinguished from the idea of attempting to remove the foreign particles from the 35 sauce while in a stationary condition. Furthermore the foreign particles are more readily made visible when flowing the sauce than when it is held stationary for the reason that the particles 40 are shifted or turned when traveling downwardly on the inclined surface of the table. Furthermore the method preferably includes the idea of illuminating the sauce when operating the suction devices for removing the foreign particles, 45 which, in the present instance, is effected by spreading or flowing the sauce on an illuminated glass plate or other transparency.

The means for removing the foreign particles from the sauce by suction, preferably comprises 50 a plurality of nozzles connected with suitable suction producing means such, for example, as one or more vacuum chambers or containers in which are collected the foreign particles and such small quantities of the sauce as may adhere to 55

the particles or be contiguous thereto at the time the particles are being sucked up by the nozzles. Control or manipulation of the nozzles is effected by hand, preferably by different persons operating side by side at each refining unit.

Referring to the drawings, the cooling tank which receives the sauce from the cooking apparatus is indicated at 10, the sauce being discharged to the tank through the supply pipe 11, under pressure produced by suitable means, not shown. The pipes 12 shown connected with the tank constitute the supply and discharge connections for the cooling fluid to be circulated through the tank.

15. The apparatus for filling the cans with the sauce, after it has been refined or clarified, is designated generally by the reference numeral 13 and includes a reservoir or receiver 14 to which the sauce is discharged from the refining means 20 as described hereinafter.

A thin layer or film of the sauce to be refined is shown at 15 on suitable supporting means such, for example, as the table 16 which is preferably formed of glass or other transparent or translucent material in order that the film of sauce may be illuminated so that the foreign particles indicated at 15a will stand out and be rendered more noticeable, whereby to facilitate removal of the same by means of the suction nozzles described hereinafter.

30. A suitable source of light may be provided beneath the table or glass plate 16 for illuminating the layer of sauce thereon such, for example, as one or more electric lights 17 having reflectors 18 for directing the light rays upwardly beneath the glass.

35. A suitable frame is provided for supporting the table, comprising the front and rear uprights 19 and 20 connected by the upper and lower transverse tie members 21 and 22 and by the longitudinally extending tie members 23, only one of which is shown.

The table 16 is carried by suitable supporting means 24 pivoted at 25 upon the upright frame members 20, the supporting means being adjustably carried by one or more links 26 pivotally connected therewith and slotted at 27 to receive a clamping bolt 28 extending through the end frame member 21, as shown in Fig. 2. By this means the inclination of the table 16 may be varied to increase or decrease the rate of flow of the sauce thereon as may be desired, depending on the degree of fluidity of the sauce and also on the time required to effect removal of the foreign particles under different operating conditions.

40. The sauce may be discharged to or spread upon the table or belt by any suitable means or by any preferred method, but is preferably fed to an open trough-like receptacle 29 disposed adjacent the rear edge of the table or belt and slightly above the same and supported by suitable brackets 30, as shown in Fig. 2. The trough is provided with a series of closely related perforations or slots 31 for discharging the sauce in a thin film or stream upon the table. A suitably supported strip 32 may be interposed between the trough and the table or belt for spreading or controlling the flow of the sauce upon the table. The strip 32 may be made vertically adjustable if desired to further regulate or control the flow of the sauce, as for example to vary the depth of the film or layer flowing downwardly upon the table.

45. The sauce is discharged from the lower edge of the table to a chute 33 having an outlet pipe 34

discharging to the reservoir or receiver 14 of the can filling machine 13, as shown in Fig. 1. The chute is provided with an upstanding inwardly curved guard 35 which overlies the point of discharge of the sauce from the table and which serves to protect the operators handling the suction devices from coming in contact with the sauce.

50. In the present apparatus, the cooked or prepared sauce is pumped through the cooler and the pipe 36 leading therefrom up to the trough or receptacle 29 by a centrifugal pump or other suitable means, not shown. A valve 37 is disposed in the outlet end of the pipe for regulating the flow of the sauce to the receptacle, the latter being open to permit any air that may be pumped through the pipe with the sauce to escape in order to avoid splashing of the sauce discharging through the apertures 31 of the trough by the passage of the air therethrough.

55. The pipe 36 is also provided with a valve 38 adjacent the cooler for closing the pipe whenever it may be desired to discharge the sauce directly to the reservoir 14 through the pipe 39 connecting the reservoir with the pipe 36.

60. Mounted adjacent to the sauce receiving table 16 are a pair of containers 40 and 41 of duplicate construction, each having supporting brackets 42 therefor attached to a wall or frame, not shown, the containers having windows 42a through which 65 to view the contents thereof. The containers are connected with a suction pump 43 by means of a pipe 44 and the branch pipes 40a and 41a leading from said pipe, respectively, to the containers 40 and 41, Fig. 1, the exhaust pipe of the pump 35 being indicated at 43a.

65. Valves 45 and 46 are interposed in the pipes 40a and 41a for closing each in order that the suction pump may be alternately connected with the containers for a purpose described herein-after. The pump shaft has a pulley 47 thereon driven by a belt 48, which in turn is driven by a pulley 49 on the shaft of an electric motor 50, the pump and motor being disposed on a support 51 carried by suitable brackets 52.

70. Extending from each of the containers 40 and 41 is a suction pipe 53 with which is connected a plurality of flexible tubes or conduits 54 having suction nozzles 55 on the ends thereof, each of the tubes being provided with a valve 56 for closing the same when desired. The tubes are also provided with hand grips 57 for controlling or operating the nozzles. The tubes are normally looped upon suitable supports 58, as shown in Fig. 1, ready for use when desired.

75. In using the suction nozzles to remove the foreign particles from the sauce, the operators will occupy positions at the front of the table, each watching a predetermined portion thereof for the foreign particles appearing in the sauce flowing thereon and each inserting the end of the suction nozzle within or adjacent to the sauce at the points at which the foreign particles appear, whereby to effect withdrawal of such particles during operation of the machine.

80. Since the pump 43 is constantly connected with one or the other of the containers 40 and 41, suction will be produced within the nozzles corresponding to said containers, with the result that the foreign particles removed from the sauce by the nozzles will be collected within the respective containers along with a certain amount of the sauce surrounding or contiguous to the various particles. It will be understood that the containers will be alternately used to collect such 85

foreign particles and that when one is in use for this purpose the other will be discharging its contents to a suitable screening device or separator such as that designated generally by the reference numeral 59 in Fig. 1, which may be of any well known design. To this end the containers are provided with outlets in their lower ends controlled by the valves 60 and connected with a pipe 61 having a centrally disposed outlet portion 62 discharging to a hopper 63 of the machine 59 for screening or separating the sauce from the foreign particles. The residue collected by the containers 40 and 41 and alternately discharged therefrom to the hopper is delivered by the latter to a relatively fine circular or cylindrical screen within the housing 64 of the separator. Rotatable within the screen are a plurality of paddles, not shown, disposed on the horizontal shaft 65 driven by a belt 66 operated by a pulley on the shaft of an electric motor 67, as shown in Fig. 1. The paddles are set at a slight angle to the longitudinal axis of the screen so that they will constantly tend to move the foreign particles and sauce mixed therewith longitudinally within the screen, said particles being moved to an outlet in the end of the screen from which extends a pipe 68 for discharging the particles from the machine. The sauce will be forced through the screen by the rapidly revolving paddles and discharged to a hopper 69 beneath the screen. The sauce thus recovered from the residue collected within the containers 40 and 41 is discharged from the hopper through a gravity feed pipe 70 to the pipe 34 leading from the hopper 33 beneath the table 16 to the receiver 14 of the can filling machine 13. Thus it will be seen that substantially all of the sauce withdrawn with the foreign particles from the refining table is recovered and delivered to the can filling machine.

In the modification shown in Fig. 4 no means is provided for reclaiming the sauce sucked up by the nozzles with the foreign particles. Otherwise the apparatus is substantially the same as that shown in Fig. 1, except that the cooler 10 and can filling apparatus 13 have been omitted. It will be understood, however, that this part of the apparatus can be used with the arrangement shown in Fig. 4 in the same manner and for the same purpose for which it is used in Fig. 1. Thus it will be seen that it is intended to omit from the arrangement shown in Fig. 4 only the colander 59 and associated parts which are employed in Fig. 1 merely for the purpose of recovering or reclaiming the sauce withdrawn from the table or belt by the suction nozzles.

It will be further understood that the mixture of sauce and foreign particles accumulating within the tanks 40 and 41 of Fig. 4 will be alternately discharged therefrom the same as in the arrangement shown in Fig. 1, and that the mixture will be carried off by a waste pipe 62a to any desired point, said waste pipe being connected with the pipe 61, as shown in Fig. 4.

The nozzles shown in Fig. 4 are the same as those shown in Fig. 1 except that each is provided with a valve for closing the same when desired such, for example, as the valve shown in Fig. 6. In this arrangement the nozzle tube is indicated at 71, the inner end of which is suitably connected with one side of a valve casing 75. The opposite side of the casing is threaded upon a nipple 76 forming an extension of the hand grip 57 which is the same as that shown in Fig. 1. The valve casing 75 has a valve 77

therein provided with a transverse bore 78 which, when the valve is in the normal position shown in Fig. 5, serves to establish communication between the nipple 76 and nozzle tube 71. The valve is normally held in the position shown in Fig. 5 by a spring 79. Closing of the valve is effected by employing the thumb or finger to force the valve operating member 80 inwardly to the position shown in Fig. 6, against the pressure of the spring 79, the valve when released being returned to normal position by the spring. The closing of the valves to prevent suction through the nozzles may be momentarily effected whenever desired.

A modified form of a nozzle is shown in Fig. 5, which comprises the bent tube 71a having an enlarged end 72 over the mouth of which is extended a relatively fine screen 73 which will permit the sauce containing the foreign particles to pass therethrough, but which will intercept and retain such particles thereon. The screen is suitably secured on the nozzle preferably by means of a clamping ring 74. Removal of the foreign particles from the screens may be effected from time to time by dipping the ends of the nozzles in water or other liquid, or by moving them in contact with suitable means which will operate to brush, scrape, or otherwise remove said particles from the screens, it being understood that when thus cleaning the nozzles that the valves 71 will be held in closed position as shown in Fig. 6. With this method of reclaiming the sauce, the colander 59 shown in Fig. 1 will be omitted, in which case the pipe 62 will be extended to and connected with the discharge pipe 34, as is the pipe 70 in Fig. 1.

Instead of flowing the sauce by gravity on an inclined board or table shown in Fig. 2, it may be discharged in a thin layer upon and advanced by a belt such as that shown at 16a in Fig. 7, the belt being carried by pulleys 16b supported by suitable means, not shown. In this modification the sauce is discharged through a supply pipe 36a to a trough-like receptacle 29a, provided with a series of closely related perforations or slots 31a for discharging the sauce in a thin film or layer upon the belt. A suitably supported strip 32a may be interposed between the trough and the belt for continuously spreading the sauce upon the belt during movement of the latter. The sauce is discharged by the belt to a chute 33a corresponding to the chute 33 of Fig. 2 and having an outlet pipe, not shown, corresponding to the pipe 34 of Fig. 1. The inner edge 34a of the chute is placed adjacent the belt as shown in Fig. 7 so as to insure discharge of the sauce into the chute. The pipe 36a corresponds to the pipe 36 of Fig. 1 and will be connected with the cooler 10 in the same manner as shown in Fig. 1.

It will be understood that the nozzles shown in Figs. 1, 4, and 5 may be used to withdraw the foreign particles from the layer of sauce spread upon the belt 16a in the same manner that they are intended to be used for removing such particles from the layer of sauce flowing upon the board or table 16, Fig. 2.

It will be understood that the tanks 40 and 41 and their respective nozzles may be so located with respect to the table 16 or belt 16a as to permit either set of nozzles to be conveniently employed for the removal of the foreign particles from the sauce.

I claim:

1. The method of refining fruit sauces by

- eliminating foreign particles therefrom, comprising spreading the sauce in a thin film or layer over a supporting surface, and operating suction producing means to withdraw said particles from the sauce.
2. The method of refining fruit sauces, comprising spreading the sauce in a thin film or layer over a supporting surface, operating one or more suction nozzles to remove the foreign particles and the sauce contiguous thereto from said layer, and separating the sauce removed with the foreign particles therefrom.
3. The method of refining fruit sauces, comprising flowing the sauce in a thin film or layer on a supporting surface, employing one or more suction nozzles to remove the foreign particles and sauce contiguous thereto while flowing the sauce on said surface, and screening the material thus removed to separate the sauce from the foreign particles.
4. The method of refining fruit sauces, comprising flowing the sauce by gravity in a thin film or layer on a supporting surface and at the same time discharging it to a receiver, employing one or more suction nozzles to remove the foreign particles and sauce contiguous thereto from the flowing mass, screening the material thus removed to separate the sauce from said foreign particles, and discharging the recovered sauce to said receiver.
5. The method of refining fruit sauces, comprising spreading the sauce in a thin film or layer on a transparency, illuminating the transparent support to effectively display the foreign particles contained in the sauce, and operating suction producing means to withdraw said particles from the sauce.
6. The method of refining fruit sauces, comprising flowing the sauce in a thin film or layer on a supporting surface and discharging it to a receiver, employing suction producing means to withdraw the foreign particles from the flowing mass and the sauce contiguous to said particles, collecting the material thus withdrawn in a receptacle, discharging the material from the receptacle to a screening device, operating the screening device to separate the sauce from the foreign particles, and delivering the recovered sauce to the receiver.
7. The method of refining fruit sauces, comprising flowing the sauce in a thin film or layer on a supporting surface, alternately employing separate suction chambers and suction nozzles connected therewith to collect the foreign particles from said layer and the sauce contiguous to said particles, alternately discharging the collected material from said chambers to a screening device, and operating the screening device to separate the sauce from the foreign particles.
8. The method of refining fruit sauces, comprising flowing the sauce by gravity in a thin layer on and from a supporting surface to a receiver, alternately employing separate suction devices to collect the foreign particles from said layer and the sauce contiguous to said particles, alternately discharging the collected material to separate the sauce from said foreign particles, and delivering the screened sauce to said receiver.
9. The method of refining fruit sauces, comprising flowing the sauce in a thin film or layer on a supporting surface, operating screened suction nozzles to withdraw the foreign particles and sauce contiguous thereto from said layer, collecting the foreign particles on the screens, and periodically removing the collected foreign particles from the screens.
10. In apparatus for refining fruit sauces, a table for receiving the sauce, means for causing the sauce to spread upon the table to form a relatively thin layer thereon, and suction producing means operable to withdraw foreign particles from the sauce when spread upon the table.
11. In apparatus for refining fruit sauces, supporting means, a table on the supporting means for receiving the sauce, means for spreading the sauce upon the table to provide a relatively thin layer thereon whereby to expose the foreign particles of the sauce, and suction producing means operable to withdraw said foreign particles from the sauce, said means including a receptacle within which the foreign particles are collected.
12. In apparatus for refining fruit sauces, supporting means, a table on the supporting means inclined to the horizontal, means for discharging the sauce to the table for movement by gravity thereon in a relatively thin layer, suction producing means, and one or more suction nozzles connected with said suction producing means and operable to withdraw the foreign particles from the sauce.
13. In apparatus for refining fruit sauces, a table for supporting a relatively thin layer of the sauce, suction producing means operable to withdraw the foreign particles from said layer and the sauce contiguous to said particles, and means connected with the suction producing means for separating the sauce from the foreign particles.
14. In apparatus for refining fruit sauces, a table for receiving the sauce, means for causing the sauce to spread upon the table to form a relatively thin layer thereon, means operable to withdraw the foreign particles from said layer and the sauce contiguous to said particles, and means connected with the last mentioned means for removing from the foreign particles the sauce withdrawn therewith by said means.
15. In apparatus for refining fruit sauces, supporting means, a translucent plate on the supporting means for receiving a relatively thin layer of the sauce, means for illuminating the plate to effectively illuminate the sauce and foreign particles therein, and suction producing means operable to withdraw the foreign particles from the sauce.
16. In apparatus for refining fruit sauces, supporting means, a table on the supporting means for receiving a relatively thin layer of sauce, a container forming a suction chamber, suction means connected with said chamber, a flexible tube connected with said chamber and having a nozzle operable to withdraw the foreign particles from said layer and the sauce contiguous to said particles and through which parts of the sauce and said particles are conveyed to said chamber, a screening device connected with said container for receiving the residue collected therein, and means for operating the screening device to separate the sauce from said foreign particles.
17. In apparatus for refining fruit sauces, a table for receiving the sauce, means for discharging the sauce in a thin layer upon the table, adjacently mounted containers, suction producing means adapted to be alternately connected with said containers, flexible tubes connected with each of said containers, said tubes having suction nozzles thereon for withdrawing foreign particles from said layer of sauce and the sauce contiguous thereto.

to said particles, screening means, means for alternately discharging the residue collected in said containers to said screening means, and means for operating the screening means to separate the sauce from the foreign particles.

5 18. In sauce refining apparatus, cooling means for the sauce, container filling apparatus, a table for receiving the sauce having a surface inclined to the horizontal, means for conveying the sauce from the cooling means to said surface including means for discharging the sauce in a thin film or layer upon said surface for discharge therefrom by gravity, means for conveying the discharging sauce to said filling apparatus, a 10 suction chamber, a flexible tube connected with said chamber and provided with a suction nozzle for removing foreign particles from said layer and the sauce contiguous to said particles, screening means connected with said chamber for receiving the sauce and foreign particles accumulating therein, means for operating the screening means to separate the sauce from said particles, and means for conveying the sauce from the screening means to said container filling apparatus.

25 19. In apparatus for refining fruit sauces, a table for receiving the sauce, means for causing the sauce to spread upon the table to form a relatively thin layer thereon, suction means, a nozzle connected with the suction means for cooperation therewith to effect withdrawal of the foreign particles from said layer and the sauce contiguous to said particles, and a screen on the

nozzle for the passage of the sauce, the screen serving to intercept the foreign particles whereby to separate them from the sauce.

20. In apparatus for refining fruit sauces, a table having a surface inclined to the horizontal, 5 means for discharging the sauce in a thin film upon said surface for flow thereon by gravity in a relatively thin layer, suction means, a nozzle connected with said suction means for cooperation therewith to effect withdrawal of the foreign 10 particles from said layer and the sauce contiguous to said particles, and a screen on the nozzle for the passage of the sauce, the screen serving to intercept the foreign particles whereby to separate them from the sauce.

15 21. In apparatus for refining fruit sauces, a power driven belt, means for discharging the sauce to and for causing it to spread upon the belt to form a relatively thin layer thereon, suction producing means operable to withdraw 20 foreign particles from said layer of sauce, and means for effecting removal of the sauce from the belt during advancement by the belt.

22. The method of refining fruit sauces by eliminating foreign particles therefrom, comprising discharging the sauce to and spreading it in a thin film or layer on a moving belt, operating suction producing means to withdraw said particles from the sauce while being advanced by the belt, and removing the sauce from the belt substantially at the same rate at which it is discharged thereto.

25 WILLIAM A. SMITH.
